INVENTOR
SAMUEL S. MITTLEBURG
BY *Zoltan P. Blachly*
ATTORNEY

UNITED STATES PATENT OFFICE

SAMUEL S. MITTLEBURG, OF BROOKLYN, NEW YORK

BENDABLE UNIT

Application filed July 16, 1932. Serial No. 622,897.

This invention relates to new and useful improvements in a bendable unit for signs, window display and the like.

The invention has for an object the construction of a bendable unit adapted to inaugurate a new method of bendability and variation so that artists and others may be employed to create original designs in the display of windows and the like.

10 As a still further object it is proposed to adapt the arrangement to miniature size so as to be portable as a salesmen's sample or be used as a game for children and be a toy of educational and instructive value.

15 As a still further object of this invention it is proposed to provide a plurality of strips, a plurality of pliable bands and/or wires engaged through said strips and held separated by any desired ornamental spacers upon said wires or bands and removable wrappers mounted on said strips providing for variation of the sign.

20 As a further object it is proposed to insert sliding facing on the strips in place of the wrappers.

25 As a further object of this invention it is proposed to construct the bendable unit in a manner so that it may readily be formed and arranged for a window display and bring out the genius of the window dresser. Furthermore that it be useful as a game to test the intelligence of a child and it is adaptable for useful things about the home, such as furniture and the like.

30 As a still further object of this invention it is proposed to construct the bendable unit in a manner so that advantage may be taken of neon tubing when transparent for displaying and so the device becomes commonplace equipment in stores and the like.

35 The invention still further proposes the construction of a device as mentioned which is simple and durable and which may be manufactured and sold at a reasonable cost.

40 For further comprehension of the invention, and of the objects and advantages thereof, reference will be had to the following description and accompanying drawing, and 50 to the appended claims in which the various

novel features of the invention are more particularly set forth.

In the accompanying drawing forming a material part of this disclosure:

Fig. 1 is a perspective view of a strip for 55 use in a bendable unit according to this invention.

Fig. 2 is a perspective view of a modified form of strip and wrapper used in conjunction therewith.

Fig. 3 is a perspective view of a still further modified strip.

Fig. 4 is a perspective view of still another modified strip.

Fig. 5 is another perspective view of still 65 another modified strip.

Figs. 6, 7, and 8 are perspective views of strips for use in bendable signs and constructed according to various modified forms 70 of the invention.

Fig. 9 is a perspective view of a bendable sign constructed according to the invention.

Fig. 10 is a perspective view of another bendable sign constructed according to the invention.

Fig. 11 is a perspective view of a chair constructed from the units of the elements of the bendable unit.

Fig. 12 is a perspective view of another sign 80 constructed according to this invention.

Fig. 13 is a perspective view of still another form of sign.

Fig. 14 is a perspective view of a corner construction from elements according to this invention.

Fig. 15 is a fragmentary view of one of the bands used in the unit.

Fig. 16 is a perspective view of one of the wires used in the unit.

The bendable sign according to this invention comprises a plurality of strips connected together flexibly by a plurality of pliable bands and/or wires parallel and spaced from each other and passing through said strips, a plurality of substantially spherical or ornamental spacers between said strips and upon said wires and removable wrappers or facing that slides over the strips in place of wrappers. More particularly in Fig. 1 a strip 10 has been illustrated substantially of oblong 100

shape and having openings 13 parallel to each other near the top and bottom and a central opening 14 parallel to said openings 13, and all of said openings extending from side to side through the strip. Wires, indicated by the dot and dash lines 15 are intended to pass through the openings 13 and hold together the various strips as previously explained. Spacers indicated by dot dash lines 17 are to be used between the strips. A pliable band 18 is shown in dot and dash lines engaged through the opening 14.

In Fig. 2 a modification has been disclosed in which there is a block 20 formed with the 15 passages 13 and a central passage 21 for the band. The central passage 21 is of groove mortice construction. Along opposite sides of the block 20 and extending from top to the bottom there are formed grooves 22 into 20 which the edges 23 of a wrapper 24 may be engaged. The wrapper 24 may be ornamented or inscribed with some letter or design. The groove 22 should be sufficiently close to the passages 13 so that the spacers 17 serve to 25 firmly hold the edges 23 within the grooves when the bendable unit is completely assembled.

In Fig. 3 another variation has been disclosed in which a strip 25 has been shown 20 formed with a pair of spaced inclined slots 26 extending from side to side and adapted to receive the pliable wire and also formed with a central slot 27 extending from side to side and adapted to receive the band. The strip 25 is formed with over hanging sides 28 forming 35 tracks into which a facing indicated by the dot and dash lines 29 may be slipped. The edges of the strips 25 may be suitably covered by a channel member indicated by the 40 dot and dash lines 30.

In Fig. 4 another variation of the invention has been disclosed in which a strip 31 is shown formed with the passages 13 and with 45 a central passage 32 adapted to be placed upon a band. This strip is also formed with grooves 22 to receive and hold the wrapper 23. At the top and bottom ends of the strip 31 there are grooves 33 extending longitudinally and adapted to receive corresponding 50 projections 34, from strips 35 adapted to be interconnected with each other and form a frame or edge for the bendable unit.

In Fig. 5 another variation has been disclosed in which a strip 25 has been shown provided 55 with the grooves 26 and a passage 27 as previously explained relative to Fig. 3 but distinguishing from this figure in the provision of a tongue 36 at the top and bottom adapted to engage within the channel member 60 37 to form the edges of the bendable sign.

In Fig. 6 another variation of the strip has been disclosed which is similar to the strip shown in Fig. 1, corresponding parts 65 may be recognized by the same reference numerals but distinguishes in the provision upon

one face of overlapping sides 38 forming a track in which a slide wrapper, sliding pieces or parts 39 may be engaged.

In Fig. 7 another variation of the invention has been disclosed in which a strip 40 is shown and comprises an interior core 41 and a cushion covering preferably of canvas or hose and seamless, indicated by numeral 42 both covering and the core member 41 are formed with the passages 13 and 14 previously described. Straps so covered or upholstered may be used for furniture, as for example, shown in Fig. 11. In this figure a plurality of strips have been shown adjacent each other and encircling a seat 43 in a manner so as to form a chair. The upholstered strips 40 are separated from each other by spacers 17 as previously explained relative to Fig. 1.

Fig. 8 shows another variation of the invention in which a strip 44 is shown composed of spring sheet metal bent so as to be hollow and have in-turned ends 45 upon one of the sides adapted to clamp paper or similar material. Wires 15, and a band 18 are 90 adapted to engage through the strip 44 similarly as described relative to Fig. 1.

In Fig. 9 a sign has been shown formed according to this invention. In detail, a plurality of strips 45 are shown held together by wire 46 passing through end apertures as previously described and in addition the provision of a band 47 passing through apertures in the strips 45. The strips 45 are held slightly separated by any design of ornamental spacers. The wires 46 are shown connected at one of their ends upon a stand composed of several blocks 49 upon a section of the wire 46 and held separated by spacers 50. Wrappers 51 are shown engaged upon the strips 45 for simulating some advertising matter.

In Fig. 10 another bendable unit has been disclosed in which one of the strips 52 is shown of different shape, namely that of a milk bottle and the other strips and wrappers being arranged to advertise the milk. In other respects this sign is similar to the one shown in Fig. 9 and corresponding numerals represent corresponding parts. The bands 47 are shown perforated for convenience in connection and attachment as shown in Fig. 15 and hereinafter further described. It will be readily understood that signs may be constructed to advertise tooth paste, cigarettes, 120 cigars, bottles and the like.

In Fig. 12 another sign has been disclosed constructed according to this invention and showing in particular the horizontal support rod 52 upon which a pair of spaced vertical finishing rods 53 are depending. Between these rods there are strips 54 separated by spacers 55 of a construction as previously explained. Reference numeral 56 indicates a fancy spacer in the form of ice cream dishes. 130

The details of the units will not be given in this description. The reference numeral 57 indicates a plurality of stencil printed or double faced signs also arranged between the posts 53. Beneath this there are located other types of strips forming lettering indicated by reference numeral 58. A fancy strip 59 is used at the bottom of the sign. Then to conclude the sign a base 60 is formed which comprises parallel rings of wire 61 and a plurality of strips 25 engaged thereof. These strips are removable in that no central band has been used and the strips engaged upon the wire 61 by reason of the grooves 26 the base of 15 the sign is shown of cylindrical shape with the strips extended in the vertical.

In Fig. 13 another ornamental effect has been disclosed in which a base 62 is formed from a plurality of strips connected with the 20 wires as previously described forming a bendable construction adapted to assume various shapes. Along one edge a plurality of letters 63 are mounted. Various types of strips are shown to compose the unit especially 25 along the first horizontal portion figuring from the left. A four dimensional letter indicated by numeral 64 is also shown. Block strips 65 separated by spacers 66 are shown supported upon a wire 67 having a portion 30 bent upon itself for forming parallel sections 68 upon which removable numbers 69 are shown according to the invention. A portion of the wire 67 may be used to support stockings 70. The other end of the wires 67 35 is shown terminated by the provision of a plurality of spacers 71 of various shapes.

In Fig. 14 ornamental fancy cut cardboards or other strips 72 are shown spaced from each other and indicated upon a band 73. 40 These spacers may be used for a sign construction.

In Fig. 15 a band 18 has been shown provided with an extension portion 75 secured therewith by screws 76 engaged through the 45 perforations of the strip. A lock 77 is shown engaged through the last perforation of the extension 75 and may be used to lock the various strips and spacers upon the band.

In Fig. 16 a wire 15 has been shown, and 50 an arrangement for an extension wire 78 being connected therewith. Particularly a threaded portion 79 upon the extension is adapted to engage within a threaded opening 80 on the end of the wire 15.

55 It is to be understood that any number of wires, bands and grooves may be used and interchanged in the various units.

In conclusion it is particularly pointed out that the strips may be plain, ornamental, 60 decorated, removable, transparent, opaque, cut out, crossed, morticed, notched, apertured and interchangeable. The spacers serve to divide the strips and also to be useful as ornaments. The band may be made plain or 65 perforated and of any staple material cut to

sufficient length and thereafter if needed extended. The wires may be present in the bendable unit in various fashions and of specific lengths and extendable by the addition of extension pieces. The wrappers may 70 be made of paper, velvet, cushions, canvas, hose or any other material that can be detachably applied.

There is an unlimited number of variations of the invention expressible in signs, games, 75 novelties and general utility purposes, but in each of these the main constituents of the invention must be present in order to obtain the bendable unit.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A bendable unit, comprising a plurality 80 of strips, a plurality of pliable members spaced from each other and passing through said strips, a plurality of substantially spherical spacers between said strips and upon said members, and wrappers upon said 85 strips detachably mounted.

2. A bendable unit, comprising a plurality of strips, a plurality of pliable members spaced from each other and passing through said strips, a plurality of any desired ornamental spacers between said strips and upon 100 said members, and wrappers upon said strips detachably mounted, said strips being oblong in shape.

3. A bendable unit, comprising a plurality 105 of strips, a plurality of pliable members spaced from each other and passing through said strips, a plurality of substantially spherical spacers between said strips and upon said members, and wrappers upon said 110 strips detachably mounted, said strips being formed with grooves for the reception of said wrappers.

4. A bendable unit, comprising a plurality 115 of strips, a plurality of pliable members spaced from each other and passing through said strips, a plurality of spacers between said strips and upon said members, and wrappers upon said strips detachably mounted, said strips being provided with covering material, cushioned or upholstered.

5. A bendable unit, comprising a plurality 120 of strips, a plurality of pliable members spaced from each other and passing through said strips, a plurality of substantially spherical spacers between said strips and upon said members, and wrappers upon said strips detachably mounted, said pliable members comprising bands and wires.

6. A bendable unit, comprising a plurality 125

- of strips, a plurality of pliable members spaced from each other and passing through said strips, a plurality of substantially spherical spacers between said strips and upon said members, and wrappers upon said strips detachably mounted, said pliable members having portions parallel to each other and spaced from each other and allowing for the easy insertion of said strips.
7. A bendable unit, comprising a plurality of strips, a plurality of pliable members spaced from each other and passing through said strips, a plurality of substantially spherical spacers between said strips and upon said members, and wrappers upon said strips detachably mounted, said spacers being decorative and serving to hold the strips separated.
8. A bendable unit, comprising a plurality of strips, a plurality of pliable members spaced from each other and passing through said strips, a plurality of substantially spherical spacers between said strips and upon said members, and wrappers upon said strips detachably mounted, said spacers being decorative and serving to hold the strips separated, said wrappers having their edges terminating in the vicinity of said spacers and said spacers engaging against the edges of said wrappers for holding the strips in place.
9. A bendable unit, comprising a plurality of strips, a plurality of pliable members spaced from each other and passing through said strips, a plurality of substantially spherical spacers between said strips and upon said members, and wrappers upon said strips detachably mounted, said wrappers being flexible and engageable across the faces of said strips.
10. A bendable unit, comprising a plurality of strips having a sign thereon, a plurality of pliable members spaced from each other and passing through said strips, a plurality of substantially spherical spacers between said strips and upon said members, and wrappers upon said strips detachably mounted, and elements for connecting said strips together to frame off the sign.
11. A bendable unit, comprising a plurality of strips, a plurality of pliable members spaced from each other and passing through said strips, a plurality of substantially spherical spacers between said strips and upon said members, and wrappers upon said strips detachably mounted, said strips being formed with mortice construction.
12. A bendable unit, comprising a plurality of strips, a plurality of pliable members spaced from each other and passing through said strips, a plurality of any desired ornamental spacers between said strips and upon said members, wrappers upon said strips detachably mounted, and means for extending the length of said pliable member.
13. A bendable unit, comprising a plurality of strips, a plurality of pliable members spaced from each other and passing through said strips, a plurality of substantially spherical spacers between said strips and upon said members, wrappers upon said strips detachably mounted, and means for extending the length of said pliable member, and means for holding said strips from moving off said pliable members.
14. A bendable unit, comprising a plurality of strips, a plurality of pliable members spaced from each other and passing through said strips, a plurality of any desired ornamental spacers between said strips and upon said members, wrappers upon said strips detachably mounted, and means for extending the length of said pliable member, comprising an extension portion, and means for fixing said extension portion upon said pliable member in various adjusted portions.
15. A bendable unit, comprising a plurality of strips, a plurality of pliable members spaced from each other and passing through said strips, a plurality of any desired ornamental spacers between said strips and upon said members, wrappers upon said strips detachably mounted, and means for extending the length of said pliable member, comprising an extension portion, and means for fixing said extension portion upon said pliable member in various adjusted portions, comprising a plurality of perforations formed in the pliable member, a plurality of perforations formed in the extension portions, and screws engaging through said perforations.
- In testimony whereof I have affixed my signature.
- SAMUEL S. MITTLEBURG.
